John Doggart, Macclesfield, England, assignor to V & E Friedland Limited, Macclesfield, England

Filed July 19, 1971, Ser. No. 164,183

Claims priority, application Great Britain May 14, 1971

Term of patent 14 years

Int. Cl. D31

U.S. Cl. D72—1 B

FIG.1

FIG.3

FIG.2

FIG.4

FIG. 5.

FIG. 6.

FIG. 7.

FIG. 1 is a front perspective view of a front cover of a wall chime showing my new design;

FIG. 2 is a top plan view thereof;

FIG. 3 is a bottom plan view thereof;

FIG. 4 is a side elevational view thereof;

FIG. 5 is a rear elevational view thereof;

FIG. 6 is a cross-sectional view taken on line 6-6 of FIG. 5;

FIG. 7 is a cross-sectional view taken on line 7-7 of FIG. 5.

I claim:

The ornamental design for a front cover of a wall chime, substantially as shown.
